UNITED STATES PATENT OFFICE.

GEORGE C. HESTER, OF CHICAGO, ILLINOIS.

VENTILATED-STORE-FRONT CONSTRUCTION.

1,083,830.

Specification of Letters Patent. Patented Jan. 6, 1914.

Application filed February 9, 1911. Serial No. 607,670.

To all whom it may concern:

Be it known that I, GEORGE C. HESTER, of Chicago, in the county of Cook, and in the State of Illinois, have invented a certain 5 new and useful Improvement in Ventilated-Store-Front Construction, and do hereby declare that the following is a full, clear, and exact description thereof.

My invention relates to the supporting 10 frame work of the large plates or panes of glass used in store front construction, and the object of my invention is to provide a frame construction which will be of simple form so as to be capable of inexpensive 15 manufacture and easy assemblage of parts in setting up the glass and yet furnish a substantial or strong support for the glass; which will provide adequately for drainage and ventilation, and which, withal, will be 20 handsome in appearance, and for the attainment of the object of my invention it consists in the construction substantially as hereinafter specified and claimed.

In the accompanying drawings—Figure 25 1 is a perspective view of a portion of a store front embodying my invention; Fig. 2 a cross section thereof; and Fig. 3 a detail view in perspective of the flexible nut and screw fastening device shown separated from 30 each other.

In the embodiment of my invention illustrated in the drawings, the sill 10 and the floor 11 are, as usual, of wood, the front edge 35 of the floor rising vertically from the sill and in the angle formed by the front edge of the floor and the upper side of the sill is placed the sheet or pane of glass 12. The front edge of the floor and the upper surface 40 of the sill are covered by a rail 13 formed of sheet metal, preferably, but not necessarily, copper. The sheet or pane of glass on its inner side bears against the outer vertical face of the rail 13 and at its bottom edge is supported by the horizontal member 45 of said rail, blocks or pieces 14 of yielding material, preferably, being interposed between the edge of the plate or pane and the rail beneath. On its outer face the plate or 50 pane of glass is engaged by a bar 15 made of sheet metal molding, which bar or rail also bears upon the upper side of the horizontal member of the rail 13 in front of the plate or 55 pane of glass, said bar having the downwardly turned flange 16 that engages the glass and a horizontally inwardly turned flange 17 that affords a good bearing on the

sill-engaging portion of the rail 13. Midway between said flange portions of the bar 15 there are holes for the passage of fastening screws 18 which extend obliquely or at an angle, and enter each a metal nut or threaded socket 19 which rises at the desired angle from the horizontal member of the rail 13, and to which it is secured by a horizontally extending tang or tail 20 which has 60 a single rivet or pin 20^a passing through it to fasten it to said rail 13. The rivet connection is sufficiently loose, to allow some horizontal swing of the nut, and, the tail 20 is sufficiently flexible to permit some vertical 65 movement of the nut to change its angle, if need be, to suit the angle of the screw. Thus ample, adaptability of the nut is provided for, the principle occasion for which may arise out of the use of varying thicknesses of 70 glass that result necessarily in alteration of the angle of the screw and if no compensating device were provided, the outside molding or bar 15 would not be drawn squarely 75 against the glass, as is done with my device. 80

The use of the nut gives other important advantages. The screws do not enter wood, as when wooden sills are used, and thus the rotting of wood around screw holes is avoided, and there can be no trouble from 85 insecure hold of the screws due to the wear of the wood from repeated removal of the screws. The copper, or sheet metal molding or frame can be mounted on iron, brick, stone, or any other hard substance, for by 90 the use of the nuts 20, the screws, of course, do not have to enter such hard substances. Again, the cost of manufacture is reduced, because the parts of the metal sash (the rail 95 13 and the bar 15) can be assembled at the factory, whereas otherwise, said parts would be required to be put together on the wood-work at the building. When used on a sill of stone, or other hard substance, the vertical member of the rail 13 is nailed to the wood 100 at the back thereof.

To prevent the accidental separation and loss of the screws 18, the head of each tapers outward, and the metal contiguous to the screw opening is crimped or flanged about 10 105 the screw head to form a retaining socket 18^a, a swiveled connection thus being provided for the screw.

It is important to provide for the adequate drainage of water from the inner surface of the glass and for ventilation, and heretofore in constructions for the same 110

pose this has been provided for by punching holes through the sheet metal. I avoid the necessity of punching holes for this purpose by embossing the vertical member 5 of the rail 13 outward to provide spaced or separated projections or bosses 21 at intervals and by embossing the horizontal member of said plate upward to form spaced or separated projections or bosses 22 at intervals, the pane or plate of glass engaging the bosses 21 in the one case and the lower edge of the bar 13 engaging the bosses 22 in the other case. In practice the bosses are about 10 four inches long and they are separated by 15 a space about a half an inch wide, but, of course, I do not restrict myself to any particular proportions; and preferably the bosses on the respective portions of the rail 13 are in a staggered or offset relation so 20 that the opening between adjacent bosses on the vertical member of the rail 13 will be out of alignment with the opening between adjacent bosses on the horizontal member of the rail 13, and thus the likelihood of dust 25 finding its way within the window from the outside is averted. Again this arrangement prevents the direct passage of outside air into the room. The lower edges of the bosses on the vertical member of the rail 13 30 are situated sufficiently above the lower or cut edge of the glass as to prevent any chipping or breaking of the glass by pressure of said edge against the rail surface. To provide a gutter 23 at the inner side of the 35 glass, the rail 13 at the top of its vertical member is carried upward and inward in line with the upper edges of the bosses 21 on the vertical member of the rail and said gutter portion is widened to the extent of 40 the projection or offsetting produced by the formation of the bosses 21.

Having thus described my invention what I claim is—

1. In a window construction, the combination of a bearing rail formed of sheet metal having offset or struck-up portions forming separated or spaced bosses, a glass-engaging

bar to hold the glass against certain of said bosses and itself engaging other of said bosses, and means for securing said bar in position.

2. In a window construction, the combination of a bearing rail formed of sheet metal having offset or struck-up portions forming separated or spaced bosses, a glass-engaging bar to hold the glass against certain of said bosses and itself engaging other of said bosses, and means for securing said bar in position consisting of obliquely extending screws passing through the bar.

3. In a window construction, the combination of a bearing rail formed of sheet metal having offset or struck-up portions forming separated spaced bosses, a glass-engaging bar to hold the glass against certain of said bosses and itself engaging other of said bosses, and means for securing said bar in position, said rail having a gutter formed of an upwardly and inwardly inclined flange aligning with the tops of the glass engaging bosses.

4. In a window construction, the combination of a metal rail, a glass-engaging bar for holding the glass against the rail, screws passing through holes in said bar, and nuts for the screws attached to said rail, said nuts being flexible at a point between their screws and the rail whereby lateral movement of the nuts may take place.

5. In window construction, the combination of a metal rail having members at an angle, a metal bar for confining a pane against said rail, a screw passing obliquely through said bar, and having a swiveled connection therewith, and a nut pivotally connected to the rail and flexible intermediate said pivotal connection and the screw.

In testimony that I claim the foregoing I have hereunto set my hand.

GEORGE C. HESTER.
